FRANCIS C. RUSH, OF DETROIT, MICHIGAN

ATTACHMENT FOR DOOR LOCKS AND LATCHES

Application filed May 27, 1929. Serial No. 366,322.

This invention relates generally to locks and latches and refers more particularly to an attachment for latch bolts thereof.

Heretofore it has been possible for unauthorized persons to "pick" locks and latches by inserting a suitable tool or instrument such as a knife blade between the free edge of the closure and its jamb into engagement with the usual bevelled or inclined face of the latch bolt and thereby force the latter rearwardly to retracted position.

With the present invention, however, the latch bolt cannot be retracted by any unauthorized person in such a manner due primarily to the provision in the bolt of a spring pressed plunger which is normally in the plane of the bolt but is adapted to be projected by the tool or instrument into engagement with a portion of the latch casing to prevent the latch bolt from being retracted.

In the accompanying drawing:

Figure 1 is a sectional view through a door and jamb and showing an attachment embodying my invention applied to the latch bolt;

Figure 2 is an enlarged fragmentary perspective view of the latch bolt and attachment;

Figure 3 is a sectional view taken on the line 3—3 of Figure 1;

Figure 4 is a detail perspective view of the plunger.

Referring now to the drawing, 1 is a door, 2 is a latch casing carried by the door at the free edge thereof, 3 is a reciprocating latch bolt normally projecting through a wall 4 of the casing, 5 is a jamb, and 6 is a keeper or striker plate on the jamb adapted to be engaged by the bolt 3 when the door is in closed position.

To prevent the bolt 3 from being forced rearwardly by a tool such as 7 while the door is closed, I have provided a spring pressed plunger 8 movable transversely of the bolt 3. As shown, this plunger is U-shape in form and straddles the bolt. Preferably the base 9 of the U is relatively wide and is received in a suitable slot 10 in the bevelled face 11 of the bolt, while the arms 12 and

13 of the U are received in slots 14 and 15 in opposite edges of the bolt and have inturned end portions 16 and 17 that are normally in recesses 18 and 19 in the rear face of the bolt. As illustrated in Figure 1, a coil spring 20 is in a recess 21 in the bolt in rear of the base 9 and normally holds the inturned arm portions 16 and 17 in the recesses 18 and 19 and holds the base 9 in line with the bevelled face 11. Preferably this base 9 is inclined at substantially an obtuse angle to the arms 12 and 13 so that it conforms in inclination to and constitutes a continuation of the bevelled face 11 when the plunger is in neutral or normal position. If, however, a tool such as 7 is inserted between the jamb 5 and the door 1 to pick the lock, the point 7' of the tool will engage the base 9 of the plunger and will push the latter transversely of the bolt so that the inturned arm portions 16 and 17 will extend over and constitute shoulders or abutments upon the wall 4 of the casing. As a result the bolt 3 remains motionless and can not be wedged or forced by such a tool rearwardly to retracted position.

Thus from the foregoing it will be apparent that the plunger 8 will effectively prevent locks and latches from being picked. Such a plunger is simple in construction and can be manufactured at a comparatively low cost. Moreover, the base 9 in addition to serving as a continuation of the bevelled face 11 of the bolt is relatively wide so that the surface to be engaged by the instrument or tool is of sufficient size to insure proper engagement therewith. The inturned portions 16 and 17 of the arms also serve a dual function; first, to engage the bolt and limit outward movement of the plunger; and second, to extend over the latch casing and prevent retraction of the bolt when the plunger is moved inwardly by the tool. In practise the depth of the recesses 14 and 15 is substantially equal to the thickness of the arms 12 and 13, and the depth of the recesses 18 and 19 is substantially equal to the thickness of the inturned portions 16 and 17 so that the arms 12 and 13 and inturned portions 16 and 17 will normally be flush with the adjacent surfaces of the latch bolt. Such plungers may

be of any shape so as to move transversely of the bolt and any number of such plungers may be used. For example, two may be used and they may be constructed to move laterally from opposite edges of the bolt into engagement with the latch casing. Moreover, one or more leaf springs may be used instead of the coil spring 20 to hold the plunger in neutral position. In fact, this construction may be used as an attachment for latch bolts, of locks and latches of various kinds, and upon closures of various descriptions, for example the plunger may be used upon the bolt of a latch on a milk chute door.

15 While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. The combination with a latch having a casing and a latch bolt movable through a wall of the casing, of a member straddling the latch bolt and movable with the bolt when the latter is moved, and movable transversely thereof into engagement with the wall aforesaid when the bolt is stationary to prevent retraction of said latch bolt.

2. The combination with a latch having a casing, of a latch bolt movable through a wall of said casing and provided with recesses, of means for preventing retraction of said latch bolt including a member of substantially U configuration having the base of the U in one of said recesses and having arms in another of said recesses, and yieldable means associated with one of said recesses for holding said member in a predetermined position relative to said latch bolt.

3. In combination, a latch bolt having recesses in opposite sides thereof and having recesses in opposite edges thereof, of a plunger having a base in a recess in one side of said bolt, having arms in the recesses in opposite edges of said bolt and having inturned arm portions in the recesses in the opposite side of said bolt, and yieldable means associated with said base for normally holding said plunger in a predetermined position relative to said bolt.

4. An attachment for latch bolts comprising a substantially U-shape member having a relatively wide base, substantially parallel arms projecting from said base and having inturned end portions.

5. In combination, a latch bolt having a beveled face provided with a recess, and a plunger having a reciprocating portion in said recess normally flush with the beveled face but compressible within the recess.

6. An attachment for latch bolts comprising a reciprocating member adapted to strad-

dle the latch bolt, said member having a base receivable within the bolt, arms projecting from the base and engageable with opposite sides of the bolt, and inturned portions at the free ends of the arms receivable in said bolt, the length of said arms being such that the inturned portion and base may be received simultaneously in said bolt.

7. In combination, a movable latch bolt having a beveled face provided with a recess, a yieldable element in the recess, and a plunger carried by the bolt having a portion normally held by the yieldable element substantially flush with the beveled face but compressible in the recess against the tension of said yieldable element.

8. In combination, a movable latch bolt, a plunger movable with but adapted to remain stationary relative to the latch bolt when the latter moves, and adapted to be moved relative to the bolt after the latter is stationary, and yieldable means resisting the last mentioned movement of the plunger.

In testimony whereof I affix my signature.

FRANCIS C. RUSH.
